[57] **CLAIM**

The ornamental design for a container for car cleaning equipment, as shown and described.

DESCRIPTION

FIG. 1 is a front perspective view of a container for car cleaning equipment showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof;

FIG. 7 is a front perspective view thereof, with the handle in a lowered position; and,

FIG. 8 is a rear perspective view thereof with the handle in another lowered position.

FIG.1

FIG.2

FIG.3
